UNITED STATES PATENT OFFICE.

MARTIN HOFF, OF FRANKFORT-ON-THE-MAIN, GERMANY, ASSIGNOR TO KASPAR-GETREIDESCHÄLIMASCHINE G. M. B. H., OF OFFENBACH-ON-THE-MAIN, GERMANY, A CORPORATION OF GERMANY.

MACHINE FOR SHELLING AND POLISHING GRAIN AND THE LIKE.

Original application filed June 12, 1924, Serial No. 719,519, and in Germany July 17, 1923. Divided and this application filed February 6, 1926. Serial No. 86,433.

The invention relates to machines for shelling, polishing and otherwise treating grain, legumes, clover seed and the like and more particularly to machines of this class which include shelling chambers with paddles mounted therein. The invention contemplates the provision of an improved construction and arrangement of paddles, in the shelling chambers, whereby the treatment of 5 the material is rendered more efficient and uniform and the operation of the machine is simplified. Other more specific objects of the invention will appear from the description hereinafter and the features of 10 novelty will be pointed out in the claims. The present application is a division of another application filed by me in the United States Patent Office on June 12, 1924, Serial #719,519.

20 In the accompanying drawings, which illustrate examples of the invention without defining its limits, Fig. 1 is a front elevation of the machine; Fig. 2 is a fragmentary side view, partly in section showing one 25 form of the novel arrangement of paddles; Fig. 3 is a fragmentary cross-section thereof; Fig. 4 is a view similar to Fig. 2 showing another form of paddles; and Figs. 5 and 6 are views corresponding to Figs. 2 30 and 3 showing still another arrangement of paddles.

The machine itself may be of any suitable construction and as shown consists of a stationary casing A in which a plurality of cylindrical shelling chambers 1, 2 and 3 are located in axial registry with each other; the chambers are separated from each other by means of intermediate chambers 4 and 5 as shown in Fig. 1. Suitable means such as 35 shown for instance in United States Patent #1,375,592, issued to Leopold Kaspar on April 19, 1921, may be provided whereby communication between adjacent shelling chambers is established at the proper times 40 in the operation of the machine. The intermediate chambers 4 and 5 may include suitable apertures through which ventilation of the shelling chambers may take place as in the aforesaid patent; likewise a suitable fan 45 may be provided, as in said patent, for removing substances emanating from the shelling chambers. The substances referred to 50 may, if desired, be collected, for instance by

means of a worm conveyor as in said patent, and conveyed to the compartment in which the fan is located. To permit the substances, which generally comprise dust, chaff, shelled husks and the like, to pass out of the shelling chambers 1, 2 and 3, the latter may be provided with sieves suitably located for the intended purposes and of such mesh as to prevent the grain or the like from passing therethrough; this sieve arrangement may also correspond to that of the aforesaid patent. As so far described the machine may be of any customary and well known construction, the parts described forming no part of the invention except in combination with features to be more fully set forth hereinafter.

In the illustrated example of the machine, the shelling chambers 1, 2 and 3 are provided with movable covers 6, 7 and 8 which control openings in the shelling chambers and are operated at the proper time and in predetermined sequence by suitable mechanism to permit the material to be transferred from one shelling chamber to an intermediate chamber and from thence to the next adjacent shelling chamber. The means whereby the material is introduced into the machine and transferred from chamber to chamber may be of any suitable type and as shown comprises a series of compartments C each of which is in registry with the aforesaid openings of the shelling chambers 1, 2 and 3 respectively. The compartments C in turn are located above and communicate with a sub-casing D fixed upon the casing A and extending lengthwise thereof as shown in Fig. 1; the sub-casing D is provided at the proper points with chutes E which lead to the interior of the intermediate chambers 4 and 5, the latter in turn being provided 85 interiorly with chutes F communicating respectively with the interior of the shelling chambers 2 and 3 as shown in Fig. 1. The sub-casing, by means of a chute G, further communicates with a hopper or the like 9 located at one end of the machine. A conveying screw H is mounted within the sub-casing D and is carried by a shaft I journaled in suitable bearings and projecting beyond the sub-casing at one end thereof; a pulley J is fixed upon the projecting portion of said shaft I and is connected by means of a belt 90

K with a pulley L secured upon the main shaft 10 to be more fully referred to hereinafter.

The illustrated machine may otherwise be constructed and arranged to operate in the manner set forth and illustrated in the application of which this application is a division.

As illustrated in Figs. 2 to 6 the walls 11 of the shelling chambers 1, 2 and 3 are provided upon their inner faces with linings 12 of a character and type suitable to the treatments to be carried out in said chambers. Within the latter according to Figs. 2 and 3, 15 paddle wheels 13 are mounted upon the shaft 10 so as to rotate therewith, the peripheries of said wheels being spaced from the linings 12. Upon their peripheries the paddle wheels 13 are provided with a series of 20 spaced paddles 14 which are constructed in the form of thin plates of suitable material. The paddles 14 are movably or pivotally attached to the wheels 13 by means of stirrups or eyelets 15 fixed upon said wheels and engaged in suitable apertures in the paddles; the latter are thus capable of independent swinging movements relatively to the wheels and to each other and are enabled to swing to either side of a radial position. Because 25 of the fact that the paddles are constructed in the form of thin plates they may be located in close proximity to each other upon the wheels whereby the efficiency of the machine for its intended purposes is materially increased.

In the form shown in Fig. 4 the paddles 14^a, which are preferably also in the form of thin plates, slightly curved, are provided with lugs 16 which are pivotally mounted 40 upon rods or the like 17; the latter are fixed upon the paddle wheel 13^a and constitute the means whereby said paddles 14^a are pivotally supported upon said wheel. The paddles are all provided with rearward extensions 18 45 which serve as counterweights and absorb a part of the centrifugal force developed in the paddles 14^a when the machine is in operation; at the same time the extensions 18, by engagement with stops 19 located at the proper points upon the wheel 13^a, may arrest the outward movement of the outer paddle portions and thus predetermine their outermost positions. The latter are so calculated that the space between the outer edges 55 of the paddles and the inner surfaces of the shelling chambers, corresponds approximately to the thickness of a kernel or other unit of the material being treated.

In some cases the stops 19 may be adjustably arranged on the wheel 13^a to vary the outermost position of the paddles 14^a. Furthermore, if desired, the pivots of the paddles may be adjustable on the wheel in radial directions, by shifting either the lugs 16 or the rods 17. In this form also, the paddles

14^a may be located in close proximity to each other on the wheel 13^a; this close arrangement of the paddles avoids the possibility that the kernels or other units of material will assume positions transverse to the paddles in which case only the points of said kernels would be acted upon.

In the form illustrated in Figs. 5 and 6 the wheels 13^b are provided with fixed blades 20 on which the thin paddles 14^b are pivotally mounted by means of links or the like 15^b; as shown in Fig. 6 each of the paddles 14^b consists of a plurality of adjacent and independently movable sections. If desired the blades 20 may be adjustable upon the wheels 13^b in radial directions in order to vary the adjustment of the paddles with respect to the linings 12 of the shelling chambers.

Assuming that the various adjustments required in the mechanical parts of the machine have been made, and that the apparatus is in operative condition, it being understood that grain or other material is contained in each of the shelling chambers 1, 2 and 3, the operation will be as follows: 85 Suitable power being applied to the pulley N, the main shaft 10 of the machine will be rotated and accordingly will cause the paddles 14, 14^a, 14^b, as the case may be, to travel in proximity to the lining 12 of the various 95 shelling chambers 1, 2 and 3.

As the paddle wheels 13, 13^a, 13^b, as the case may be, are rotated, the paddles 14, 14^a, 14^b under the influence of centrifugal force are thrown against or caused to engage the grain or the like to be shelled or otherwise treated in the chambers 1, 2 and 3, the arrangement being such that said paddles may easily yield under any pressures exerted by the material in question. As the paddles do 105 not engage the lining 12 of the shelling chambers at any time, abutments or stops for said paddles are not required.

In the present machine all of the shelling chambers simultaneously contain grain or other material, so that during a given period of time, the shelling or other treatment takes place simultaneously in all of the chambers. After the treating period has passed, it is followed by a likewise predetermined period 110 of time, during which a charge of completely treated material is discharged from the terminal chamber 3, after which partly treated charges of the material are transferred from the shelling chamber 2 to the shelling chamber 1 120 and then from the shelling chamber 1 to the chamber 2; after the transfer from the chamber 1 has taken place a new charge is introduced into the same. This cycle of operations is repeated in continuous sequence 125 throughout any given period of operation of the machine.

The arrangement of paddles avoids undesirable smashing of the material, renders unnecessary the use of springs for operat- 130

ing said paddles and at the same time avoids excessive weight therein. In the present case, the paddles because of the relatively light weight, and by the action of centrifugal force are pressed against the grain or other material to be treated with a relatively light pressure, so that injury to the kernels cannot take place; that is to say, the paddles have a relatively weak working pressure. In order to increase the yieldability of the paddles, the latter may consist of a plurality of independent sections as illustrated in Fig. 6. These sections are capable of independent movements and may yield independently under the action of material under treatment. With the above arrangements, a complete and uniform shelling or other treatment is provided with a minimum of power, and at the same time, the efficiency of the machine is materially increased. The kernels or other material when in the shelling chambers are forced to assume the form of a band-like layer which passes between the paddles and the lining of the chambers and thus has a uniform and relatively small depth; as a result of this the shelling operation may progress at a relatively high speed. The arrangement further is such that abutments for the paddles are not necessary as the length of the paddles is so determined that, in their radial position upon the paddle wheel, they just pass the lining of the shelling chambers and are capable of moving rearwardly with respect to the direction of operation. The band of material may as a matter of fact be reduced in depth to the thickness of a single kernel.

Various changes in the specific form shown and described may be made within the scope of the claims without departing from the spirit of my invention.

I claim:

1. In a machine of the kind described, the combination of a rotatable wheel, and a plurality of paddles connected therewith loosely to swing about axes parallel to the axis of the wheel, and each constructed of thin, relatively light material adapted to develop a relatively light centrifugal pressure upon the material being treated, said paddles being located in close proximity to each other.

2. In a machine of the kind described, the combination of a rotatable wheel, a plu-

rality of paddles pivotally mounted upon said wheel to swing to either side of a radial position.

3. In a machine of the kind described, the combination of a rotatable wheel, a plurality of paddles and eyelets whereby said paddles are pivotally connected with said wheel.

4. In a machine of the kind described, the combination of a rotatable wheel, a plurality of paddles, lugs on said paddles and pivot rods carried by said wheel and passing through said lugs to pivotally attach said paddles to said wheel.

5. In a machine of the kind described, the combination of a rotatable wheel, a plurality of paddles and pivotal connections whereby said paddles are mounted upon said wheel, said connections being adjustable in radial directions relatively to said wheel.

6. In a machine of the kind described, the combination of a rotatable wheel, a plurality of paddles, pivotal connections between said paddles and wheel and rearward extensions on said paddles constituting counterweights against which centrifugal force is operative.

7. In a machine of the kind described, the combination of a rotatable wheel, a plurality of paddles pivotally mounted upon said wheel and provided with rearward extensions, and stops mounted upon said wheel for engagement by said extensions to predetermine the outermost positions of said paddles.

8. In a machine of the kind described, the combination of a rotatable wheel, a plurality of blades arranged upon said wheel and paddles movably connected with said blades.

9. In a machine of the kind described, the combination of a rotatable wheel, a plurality of blades arranged upon said wheel and paddles movably connected with said blades, the latter being adjustable on said wheel in radial directions.

10. In a machine of the kind described, the combination of a rotatable wheel, a plurality of plates arranged upon said wheel and paddles movably connected with said plates, said paddles each comprising a plurality of contiguous sections freely movable independently of each other.

In testimony whereof I have hereunto set my hand.

MARTIN HOFF.
